UNITED STATES PATENT OFFICE

FREDRICH OLSEN AND CLARENCE J. BAIN, OF DOVER, NEW JERSEY

APPARATUS FOR TESTING EXPLOSIVES

Application filed August 30, 1928. Serial No. 303,088.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to us of any royalty thereon.

5 This invention relates to an apparatus for testing explosives.

The object of this invention is to provide an apparatus into which an explosive train may be quickly and conveniently loaded for 10 the purpose of testing its efficiency and effectiveness under different conditions and the rate of detonation of an explosive constituting an element of the train.

With the foregoing and other objects in 15 view, the invention resides in the novel arrangement and combination of parts and in the details of construction hereinafter described and claimed, it being understood that changes in the precise embodiment of the 20 invention herein disclosed may be made within the scope of what is claimed without departing from the spirit of the invention.

A practical embodiment of the invention is illustrated in the accompanying drawings, 25 wherein:

Fig. 1 is a longitudinal sectional view of the improved apparatus and

Fig. 2 is an enlarged, sectional view of the central portion of the apparatus.

30 Referring to the drawings by numerals of reference:

The apparatus consists of a series of adjustably connected tubes, the bores of the end tubes 5 and 6 being of less diameter 35 than the bore of the intermediate tube 7 and serving to confine between their ends elements of an explosive train which are disposed within the tube 7. The tube 5, which acts as a guide for a drop weight 8 40 is threaded internally to the intermediate tube while the tube 6, which contains a bursting charge 9, is attached to the intermediate tube by a coupling sleeve 10. The lower end of the tube 6 is closed by a cap 11.

45 The explosive train confined within the tube 7 consists of a block 12, mounting a firing pin 13, a carrier 14 in which is placed a detonator 15, and a casing 16 containing a booster charge 17. In the assembly of 50 these units there is shown an imperforate

disk or disks 18 interposed between the detonator and the booster and a ring 19 placed between the booster and the bursting charge to establish an air gap 20. The disk and ring may be interchanged and their thickness varied in conducting comparative tests to determine the efficiency of the detonator and booster. 55

In order that the rate of transmission of the detonating wave may be ascertained, 60 spaced wires 21 are inserted through the charge and its tube and are in operative connection with a recording device (not shown) which will register the time of movement of the wires. 65

Tests on the bursting charge and its container and on the effectiveness of individual elements of the explosive train and its holders or of various combinations of particular elements may readily be conducted. 70

The apparatus is functioned by removing a pin 22 which allows the drop weight to strike the firing pin normally held by a shear pin 23.

We claim:

1. A testing apparatus including a container formed of adjustably connected tubes, the bores of the end tubes being smaller than the bore of an intermediate tube, a bursting charge chamber constituted by one 80 end tube, an external coupling between said tube and the intermediate tube, spaced impulse transmitting members in the bursting chamber, members arranged to carry an explosive train confined between the end 85 tubes, separating members positionable between the individual elements of the explosive train members and between an end explosive train member and bursting charge chamber and means in the other end tube 90 for functioning the explosive train. 95

2. A testing apparatus including a container formed of adjustably connected tubes, the bores of the end tubes being smaller than the bore of an intermediate tube, a bursting charge chamber constituted by one end tube, an external coupling between said tube and the intermediate tube, members arranged to carry an explosive train confined between the end tubes, separating members 100

positionable between the individual elements of the explosive train members and between an end explosive train member and bursting charge chamber and means in the other 5 end tube for functioning the explosive train.

3. A testing apparatus including a container formed of adjustably connected tubes, the bores of the end tubes being smaller than the bore of an intermediate tube, a 10 bursting charge chamber constituted by one end tube, an external coupling between said tube and the intermediate tube, members arranged to carry an explosive train confined between the end tubes and means in the other 15 end tube for functioning the explosive train.

4. A testing apparatus including a container formed of adjustably connected tubes, the bores of the end tubes being smaller than the bore of an intermediate tube, a 20 bursting charge chamber constituted by one end tube, an explosive train carrier confined between the end tubes and means in the other end tube for functioning the explosive train.

5. A testing apparatus embodying spaced 25 tubes, a hollow member connecting the tubes and a carrier arranged to contain an explosive to be tested wholly confined within the hollow member and between the tubes.

FREDRICH OLSEN.
